ELECTRODYNAMIC MAGNET SYSTEM FOR
MICROPHONES, LOUDSPEAKERS, OR SIM-
ILAR DEVICESRoelof Vermeulen and Arend Thomas van Urk,
Eindhoven, Netherlands, assignors to Radio
Corporation of America, a corporation of
DelawareApplication March 6, 1928, Serial No. 259,445.
Renewed December 31, 1931. In The Netherlands March 25, 1927

11 Claims. (Cl. 179—115.5)

The invention relates to an electrodynamic magnet system for microphones, loud-speakers or similar devices provided with wire windings which are movably arranged in a magnetic field.

- 5 The invention has for its object to guide these windings during their movements in such a manner that at all frequencies and especially at the lower ones an efficiency is obtained which is as favorable as possible.
- 10 According to the invention, when the windings are moving in the magnetic field, they are kept centered by one or more layers of a substance which possesses a slightly elastic but strongly damping property. The slightly elastic properties involve that the directing force which moves the windings back into their middle-position, is small with the result that the natural frequency of the oscillating portion of the magnet system is very low. If the radiated sound energy is 15 graphically plotted for various frequencies, their curve is obtained which shows a peak at the natural frequency of the oscillating portion of the magnet system. When, consequently, the magnet system oscillates at that frequency, the 20 radiated sound energy will be considerably greater than at other frequencies, which is harmful to the sound reproduced. This disadvantage can be eliminated by damping the movement of the oscillating portion of the magnet 25 system and thereby smoothing out the peak.

The magnet system according to the present invention has the advantage that the point of natural resonance comes to lie low while at the same time a strong damping is obtained. Especially at frequencies ranging from 150 to 500 the efficiency of the system will be very favorable.

In a particular embodiment of the invention in which the magnet system is provided with an annular coil which is movably arranged in an annular magnetic field, this annular coil is kept centered by discs made of a substance which possesses the above mentioned properties, said discs being secured to the poles or to parts of the magnet system which are immovably connected to the said poles. The coil may be secured to the discs but should preferably not be connected thereto.

In a suitable construction, a disc is further secured to the central pole, another disc being secured to the annular pole.

The substance which has the abovementioned properties may consist of textile fabric such as velvet or flannel, but it may also consist of a substance such as felt.

55 The invention will be more clearly understood

by referring to the accompanying drawing in which

Fig. 1 is a graph showing the value of the radiated sound energy at various frequencies of the magnet system according to the invention and

Fig. 2 is a sectional view through the driving mechanism of the invention.

In Figure 2, poles 2 and 3 of a permanent or electromagnet produce together an annular magnetic field in which a coil 4 is movably arranged. The coil 4 is wound on a small tube of cardboard which is directly secured to a cone 5. A felt layer 6 is secured to the pole 2 by means of a screw 11, and an annular felt layer 7 is provided on the pole 3 by means of an annular copper clamping piece 8 and screws 9. The cardboard tube on which the coil 4 is wound, slides along the edges of the felt layers 6 and 7 and is thus kept centered in the annular magnetic field. The felt possesses the property that after being deformed it has only a slight tendency to return into its original position while it exerts a strongly damping influence on the movement of the coil 4. When now this coil 4 is traversed by speech modulated current, it will experience a strong damping during its movements. Instead of felt, also several layers of textile fabric such as flannel, serge etc. may be utilized, all of them showing slightly elastic but 30 strongly damping properties.

In Figure 1 is indicated the value of the radiated sound energy at different frequencies. The curve *a* shows the course of a magnet system with which the point of resonance lies very 35 low. The curve *b* indicates the course of the magnet system of Figure 2. The point of resonance lies at a frequency of 200 while the oscillations are strongly damped. It appears from the figure that tones with frequencies ranging 40 from 150 to 400 cycles reproduce considerably better.

What we claim is:

1. A translating device comprising a magnet system, a vibratile member, a hollow cylindrical member secured to the vibratile member, a coil mounted upon the cylindrical member, a fabric disk fastened to part of said magnet system and positioned to engage said cylindrical member, said fabric disk having slight elastic and 50 strong damping properties.

2. A translating device comprising a magnet system, a vibratile member, a hollow cylindrical member secured to the vibratile member, a coil mounted upon the cylindrical member, and a 55

- fabric disk and an annular fabric member fastened to the magnet system and positioned to slidably engage the hollow cylindrical member said disk being slightly elastic.
5. A translating device comprising a magnet system, a vibratile member, a hollow cylindrical member secured to the vibratile member, a coil mounted upon the cylindrical member, and a disk and an annular member of yielding material fastened to the magnet system, said disk engaging the inside of the hollow cylindrical member and said annular member engaging the outside of the cylindrical member.
4. An acoustic device of the electrodynamic type comprising an inner pole piece, an outer pole piece spaced therefrom to form an air gap, a vibratile member, a driving member secured to said vibratile member and extending into said air gap, a washer of damping material secured to said inner pole piece and extending outwardly therefrom to engage the inner surface of said driving member, and an annular washer of damping material secured to said outer pole piece and extending inwardly therefrom to engage the outer surface of said driving member.
5. An acoustic device of the electrodynamic type comprising a cylindrical pole piece, an annular pole piece spaced therefrom to form an annular air gap, a vibratile member, a cylindrical member secured thereto and extending into said annular air gap, a fabric disk secured to the top of said cylindrical pole piece and extending outwardly therefrom beyond the circumference thereof to engage the inner surface of said cylindrical member, and an annular fabric member secured to said annular pole piece and extending inwardly therefrom to engage the outer surface of said cylindrical member.
40. An acoustic device of the electrodynamic type comprising a central pole piece, an outer pole piece spaced therefrom to form an air gap, a vibratile member, a driving member secured thereto and extending into said air gap, and means for maintaining the proper space relation between said central pole piece, said outer pole piece and said driving means, said means consisting of a disk like member secured to said central pole piece and extending outwardly
- therefrom to engage said driving member, and a pair of annular members secured to said outer pole piece and extending inwardly therefrom, one of said annular members engaging said driving member and the other annular member engaging said central pole piece.
7. A sound converting device comprising a magnet system, a vibratile member, a hollow cylindrical member secured to the vibratile member, a coil mounted on the cylindrical member and a fabric disk secured to part of said magnet system and positioned to engage said cylindrical member, said fabric disc being only slightly elastic whereby after being deformed it has only a slight tendency to return to its original position.
8. A sound converting device comprising a magnet system, a vibratile member, a hollow cylindrical member secured to said vibratile member, a coil mounted on the cylindrical member, a fabric disc and an annular fabric member spaced apart and fastened to the magnet system and positioned to slidably engage the hollow cylindrical member said disc and fabric member being slightly elastic.
9. The device of the preceding claim in which the magnet comprises a central pole and an annular pole and in which said fabric disc is carried by said central pole and said annular fabric member by said annular pole.
10. A sound converting device comprising the combination of a magnet system having an annular airgap and a pole piece located within said gap, a vibratile diaphragm, a substantially cylindrical coil form connected to said diaphragm, a substantially cylindrical coil mounted on said coil form and at least two flexible members one being secured to said pole piece and engaging the interior surface of said coil form near one end thereof and the other being secured to said magnet system and engaging the exterior surface of said coil form adjacent the opposite end thereof.
11. The combination defined in claim 10 in which at least one of said flexible members is composed of material having slight elastic and strong damping properties.
